COMBINED BOOK COVER AND EASEL

Julius Bauer, Chicago, Ill.

Application December 18, 1939, Serial No. 309,740

10 Claims. (Cl. 281—33)

The present invention relates to improvements in combined book covers and easels.

An object of the present invention is to provide a combined book cover and easel which operates effectually as a book cover and also as a lap table or easel.

A further object is to provide a combined book cover and easel which when performing its functions as a book cover is neat and unobtrusive, and which may be readily set up as an 10 easel or lap table.

A further object is to provide a device of the kind referred to which is cheap to manufacture, neat in appearance and effective in operation.

Further objects will appear as the description 15 proceeds.

Referring to the drawing—

Figure 1 is a perspective view showing one 20 embodiment of the present invention;

Figure 2 is a side view of the structure shown in Figure 1 but set up as an easel or lap table and containing a book;

Figure 3 is a view showing the combined book 25 cover and lap table in its open position with a book mounted therein; and

Figure 4 is a view taken along the lines indicated by the arrows 4—4 in Figure 3.

The back wall of the combined book cover and easel illustrated in the drawing is indicated by the numeral 10. Said back wall has swingingly connected therewith the side walls 11—11, and the base portion 12 is swingingly connected with the back wall 10 and the side walls 11—11 at the lower edge 14 of said side and back walls. The back wall 10 will ordinarily be of elongated contour, the side walls 11—11 being swingingly connected to said back wall along the long edges 13—13 thereof. The base portion 12 may conveniently take the form of a truncated cone having weakened lines 15—15 conforming to the edges 13—13 of the back wall 11. As shown in Figure 1, the base portion 12 may be folded up into enclosing relationship with the back wall 10 and side walls 11—11 when said side walls 11—11 are in closed position relative to each other. When it is intended to use the device as an easel or lap table the bottom portion 12 will be flattened out and occupy an angular position relative to the back wall 10, as illustrated in Figure 2.

The numerals 16—16 indicate flaps which may be secured at the swinging edges of the side walls 11—11 and at the adjacent portions of the upper and lower edges of said swinging walls 11—11. Said flaps 16—16 extend only part of

the distance from the swinging edges of the walls 11—11 to the edges 13—13 and serve to receive and retain the covers of a book. In the illustrated embodiment of the present invention the upper portions of the flaps 16—16 are secured to the side walls 11—11 by snap fasteners, whereby the book covers may be more conveniently disposed in proper position within the book cover and removed from the book cover.

The numeral 17 indicates a strut having the hinged end portions 17a—17a. Said end portions 17a—17a may be hinged to the remainder of the strut by scoring or weakening of the material. Said end portions 17a—17a are provided with the head portions of snap fasteners, the head portions at the upper extremity of the strut 17 being indicated by the numerals 18—18. The head portion 19 of a snap fastener is located in the lower extremity 17a of the strut 17. The upper portion of the back wall 10 is provided with a plurality of pairs of studs 20 for receiving the heads 18—18. The inner side, that is—the upper side of the bottom portion 12 as viewed in Figure 2, is provided with the stud 21 for receiving the head 19 when the device is being used as an easel or lap table, as shown in Figure 2. The under side of the bottom portion 12 is provided with the stud 22 for receiving the head 19 when the book cover is in folded position, as illustrated in Figure 1.

The mode of operation of the above described embodiment of the present invention will be clear without detailed explanation. When the parts are in the position illustrated in Figure 1, the heads 18—18 of the snap fasteners will be located upon the lowermost pair of studs 20—20 and the head 19 of a snap fastener will be located upon the stud 22, thereby holding the bottom portion 12 in enclosing relationship with the back wall 10 and the side walls 11—11. A book may be located within the book cover and will be effectually covered and protected. When it is desired to set up the device as a lap table 40 or easel, the lower snap fastener head 19 will be released from its corresponding stud, and the side walls 11—11 will be separated, thereby swinging the bottom portion 12 down to approximately the position illustrated in Figure 2. The lower swinging extremity 17a of the strut 17 will be swung into such position that the snap fastener head 19 may be snapped onto the stud 21 and the device will be effective as an easel or lap table. By reason of the plurality of pairs of studs 20—20 the angularity of the position

of the book with respect to the bottom portion 12 may be chosen as desired.

It will be understood that the embodiment of the present invention chosen for illustration is only one of many that may be chosen. For example, the device may be made of a size such that it will conveniently accommodate magazines instead of books, and the flaps 16 may take various forms. For example, the bottom portion of each flap 16 may extend to a position more closely adjacent to the corresponding hinge 13, or the snap fasteners at the top of each of the flaps may be omitted, the upper portion of each flap being stitched or otherwise permanently secured to the corresponding side wall, or the upper portion of each of the flaps may extend only a short distance away from the corresponding swinging edge of its side wall 11. Moreover, it will be preferred by many to secure the pages of a book or the like directly to the back wall 10, as for example by means of the familiar ring binder for loose leaves; or the leaves of the book or the like may be permanently united to the back wall 10 by any of the well known book binding means. In the event that the leaves are secured to the back wall either permanently or removably, the flaps 16—16 may be dispensed with, if preferred.

Many other modifications of the present invention will occur to those skilled in the art. It is intended to cover all modifications that fall within the scope of the appended claims.

What is claimed is:

1. A combined book cover and easel embodying a structure having a back wall, side walls and a bottom portion, said bottom portion being hingedly carried by said back wall and side walls and being foldable to encompass said back wall and side walls or to occupy a substantially flat position in angular relationship with said back wall, and a strut hingedly supported by said back wall, the swinging extremity of said strut having means for engaging said bottom portion alternatively upon the two sides thereof for releasably holding said back wall and said bottom portion alternatively in parallel relationship or in spaced angular relationship with each other.

2. A combined book cover and easel embodying a structure having a back wall, side walls and a bottom portion, said bottom portion being hingedly connected to said back wall and side walls and being foldable to encompass said back wall and side walls or to occupy a substantially flat position in angular relationship with said back wall, and a strut member swingably carried by said back wall and having an extremity adapted to swing toward and away from the bottom end of said back wall and being provided at said swinging extremity with readily releasable fastener means for engaging said bottom portion to hold said bottom portion alternatively in encompassing relationship with said back wall and side walls or in angular relationship with said back wall.

3. A combined easel and book cover comprising a back wall and side walls hingedly connected together and a bottom portion hingedly connected to said back wall and side walls, said bottom portion being foldable around said back wall and side walls and being adapted to occupy a flat position in angular relationship with said back wall, and a swingable strut member having one extremity thereof carried by said back wall, the other extremity thereof being adapted to swing toward and away from the bottom end of said back wall, said bottom portion being pro-

vided with fastener devices for cooperating with said swingable extremity for holding said bottom portion alternatively in encompassing relationship with said back wall and side walls or in flat condition in angular relationship with said back wall.

4. In a combined book cover and easel, a back wall, side walls hingedly connected thereto, a bottom portion hingedly connected to said back wall and to said side walls, said bottom portion being swingable into encompassing relationship with said back wall and said side walls, said bottom portion, on one side thereof, being provided with a snap fastener member adjacent to its swinging extremity and on the other side thereof being provided with a snap fastener member adjacent to its connection with said back wall, and a swingable strut connected at one end to said back wall at a region spaced from said back wall's connection with said bottom portion, the swinging extremity of said strut being adapted to have fastening relationship alternatively with said two fastener members of said bottom portion whereby said strut may alternatively hold said bottom portion in encompassing relationship with said back wall and said side walls or hold said bottom wall in flat condition in spaced angular relationship with said back wall.

5. In a combined book cover and easel, a back wall, side walls hingedly connected thereto, a bottom portion hingedly connected to said back wall and to said side walls, said bottom portion being swingable into encompassing relationship with said back wall and said side walls, said bottom portion, on one side thereof, being provided with a snap fastener member adjacent to its swinging extremity and on the other side thereof being provided with a snap fastener member adjacent to its connection at one end with said back wall, a swingable strut connected to said back wall at a region spaced from said back wall's connection with said bottom portion, the swinging extremity of said strut being adapted to have fastening relationship alternatively with said two fastener members of said bottom portion, and means for selectively positioning the non-swinging extremity of said strut at a plurality of regions along said back wall whereby to provide a choice of angularity between said bottom portion and said back wall.

6. A combined book cover and easel embodying a structure having a back wall, side walls and a bottom portion, said bottom portion being hingedly carried by said back wall and side walls and being foldable to encompass said back wall and side walls or to occupy a substantially flat position in angular relationship with said back wall, the inner sides of said side walls being provided with means for holding the covers of a book or the like, and a strut hingedly supported by said back wall, the swinging extremity of said strut having means for engaging said bottom portion alternatively upon the two sides thereof for releasably holding said back wall and said bottom portion alternatively in parallel relationship or in spaced angular relationship with each other.

7. A combined book cover and easel embodying a structure having a back wall, side walls and a bottom portion, said bottom portion being hingedly carried by said back wall and side walls and being foldable to encompass said back wall and side walls or to occupy a substantially flat position in angular relationship with said back wall, the inner sides of said side walls being provided with means for holding the covers of a

book or the like, and a strut member hingedly carried by said back wall, the free end of said strut member being adapted to swing toward and away from the bottom end of said back wall and being provided at its swinging extremity with readily releasable fastener means for fastening alternatively to either side of said bottom portion to hold said bottom portion alternatively in encompassing relationship with said back wall and side walls or in angular relationship with said back wall.

8. A combined easel and book cover comprising a back wall and side walls hingedly connected together and a bottom portion hingedly connected to said back wall and side walls, said bottom portion being foldable around said back wall and side walls and being adapted to occupy a flat position in angular relationship with said back wall, and a swingable strut member hingedly carried by said back wall, the free end of said strut member being adapted to swing toward and away from the bottom end of said back wall, said strut member having a swingable extremity, said bottom portion being provided with fastener devices on the two sides thereof for cooperating with said swingable extremity for holding said bottom portion alternatively in folding relationship with said back wall and side walls or in angular relationship with said back wall.

9. In a combined book cover and easel, a back wall, side walls hingedly connected thereto, a bottom portion hingedly connected to said back wall and to said side walls, said bottom portion being swingable into encompassing relationship with said back wall and said side walls, said bottom portion, on one side thereof, being pro-

vided with a snap fastener member adjacent to its swinging extremity and on the other side thereof being provided with a snap fastener member adjacent to its connection with said back wall, and a swingable strut hingedly connected to said back wall at a region spaced from said back wall's connection with said bottom portion, the swinging extremity of said strut being adapted to have fastening relationship alternatively with said two fastener members of said bottom portion, the inner sides of said side walls being provided with means for holding the covers of a book or the like.

10. In a combined book cover and easel, a back wall, side walls hingedly connected thereto, a bottom portion hingedly connected to said back wall and to said side walls, said bottom portion being swingable into encompassing relationship with said back wall and said side walls, said bottom portion, on one side thereof, being provided with a snap fastener member adjacent to its swinging extremity and on the other side thereof being provided with a snap fastener member adjacent to its connection with said back wall, a swingable strut hingedly connected to said back wall at a region spaced from said back wall's connection with said bottom portion, the swinging extremity of said strut being adapted to have fastening relationship alternatively with said two fastener members of said bottom portion, and means for selectively positioning the non-swinging extremity of said strut at a plurality of regions along said back wall whereby to provide a choice of angularity between said bottom portion and said back wall.

JULIUS BAUER.

CERTIFICATE OF CORRECTION.

Patent No. 2,256,513.

September 23, 1941.

JULIUS BAUER.

It is hereby certified that error appears in the printed specification of the above numbered patent requiring correction as follows: Page 2, first column, line 71, claim 3, for "swingble" read --swingable--; and second column, line 39, claim 5, strike out the words "at one end" and insert the same after "connected" in line 40, same claim; and that the said Letters Patent should be read with this correction therein that the same may conform to the record of the case in the Patent Office.

Signed and sealed this 11th day of November, A. D. 1941.
